Attorney.

UNITED STATES PATENT OFFICE.

MONTAGUE HENRY BARLING, OF CAMDEN TOWN, LONDON, ENGLAND.

TOBACCO PIPE.

Application filed October 7, 1924, Serial No. 742,121, and in Great Britain May 14, 1924.

This invention relates to improvements in or relating to tobacco pipes.

In tobacco pipes of ordinary make, inconvenience is caused by moisture penetrating the bore of the pipe mouth-piece and stem and entering the bottom of the bowl, thus rendering the use of the pipe objectionable and being frequently the means whereby the bore becomes choked up.

Now, the object of my invention is to remedy this defect and to this end I provide a tube designed to be inserted into the bore of the pipe stem so that it passes into and across the bottom of the bowl, its inner end abutting against or recessed into the wall of the bowl. That portion of the tube within the bowl is formed at its upper part with a hole or holes and to the rear of this portion the top half of the centre of the tube is cut away and the channel so formed is divided into one or more compartments which serve as moisture traps. The outer end of the tube enters the mouthpiece when the latter is pushed or screwed into the stem in the usual way.

By employing my device as above described the flow of moisture into and from the pipe bowl is wholly or largely prevented and the tube provides a convenient means for cleaning the pipe bore.

In the accompanying drawing—

Figure 1 is a longitudinal vertical section of a pipe fitted with a moisture collecting tube in accordance with the invention.

Figure 2 is a longitudinal vertical section of the moisture collecting tube detached.

Figure 3 is a plan view of the tube, and

Figure 4 is a vertical section of a pipe bowl shewing a slightly modified shape of moisture collecting tube.

a is the bowl of the pipe, *b* the stem and *c* the mouth-piece thereof.

d is the moisture collecting tube which is inserted in the mouthpiece *c* and stem *b* of the pipe and extends into and across the bottom of the pipe bowl *a*, as clearly shewn in Figures 1 and 4. The inner end of the tube, that is to say, that end which is within the pipe bowl *a* is either made square and enters a recess *a*¹ in the bowl, as shewn in Figure 1, or it is bevelled and bears against the curved bottom of the bowl, as shewn in Figure 4.

e indicates the holes or perforations with which the upper part of the perimeter of the tube *d*, which is situated within the pipe bowl *a*, is provided, and *f* indicates the portion of the tube behind the perforated part *e* which is cut away so as to form a kind of trough. This trough is divided by partitions *f*¹ to form a compartment *g* which serves as a moisture trap.

As will be understood with this construction of pipe any moisture which may enter the tube *d* either from the mouthpiece *c* or the bowl *a* is trapped in the chamber *g*, thereby ensuring a clean dry smoke. The smoke passes through the perforations, *e*, into the rear end of the tube and thence over the upper edges of the partitions, *f*¹, between said upper edges and the upper portion of the bore of the stem, thus avoiding contact with the moisture collected in the traps.

Claims:

1. In a tobacco pipe, the combination with the bowl provided with a unitary stem, and mouthpiece detachably secured to the stem, of a one piece moisture trap, comprising a tube of uniform diameter, removably engaging and lying within the bore of the mouthpiece and stem, and extending into the lower portion of the bowl cavity, the end of said tube which extends into the bowl cavity being provided with a plurality of perforations communicating with said cavity, said tube having a portion provided with an unperforated wall lying within the mouthpiece, and an intermediate portion

cutaway on its upper side, and provided with partitions to effect the collection of moisture, whereby by detaching the mouthpiece from the stem, said tube will project from the stem and may be removed, cleansed and replaced.

2. In a tobacco pipe, the combination with a bowl provided with a unitary stem, and a mouthpiece detachably secured to the stem, of a one piece moisture trap, comprising a tube, of uniform diameter, removably engaging and lying within the bore of the mouthpiece and stem, and extending into the lower portion of the bowl cavity, and communicating therewith, said tube having a portion with an unperforated wall lying within the mouthpiece, and projecting be-

yond the end of the stem, and a portion between said unperforated portion and the bowl engaging portion having its upper wall cut away and having a plurality of transverse partitions, the upper edge of which are in substantial alignment with the cut away portions of the tube wall to form

receptacles for the collection of moisture, whereby, by detaching the mouthpiece from the stem, the said tube will project therefrom and may be readily removed, cleansed and replaced. 10
